UNITED STATES PATENT OFFICE.

JOHN MAITLAND, OF SWAMPSMOTT, MASSACHUSETTS, ASSIGNOR TO THE REECE BUTTON HOLE MACHINE COMPANY, OF BOSTON, MASSACHUSETTS, A CORPORATION OF MAINE.

CLUTCH MECHANISM.

No. 909,810.

Specification of Letters Patent.

Patented Jan. 12, 1909.

Application filed October 23, 1908. Serial No. 459,176.

To all whom it may concern:

Be it known that I, JOHN MAITLAND, a citizen of the United States, and resident of Swampscott, county of Essex, State of Massachusetts, have invented an Improvement in Clutch Mechanism, of which the following description, in connection with the accompanying drawing, is a specification, like letters on the drawing representing like parts.

This invention relates to clutch mechanism of the general character forming the subject-matter of United States Patent No. 718569, granted to Dixon January 13, 1903, wherein one member of a clutch, rotatable with the shaft to be driven, is thrown out of coöperation with the other member, which runs continuously on said shaft, by means including a rotary clutch-lever when the latter is arrested by a detent, movable into and out of the path of such clutch-lever. In the said patent the detent is mounted on a movable arm and is also movable thereon, such latter movement being resisted by a tension spring attached at one end to the arm and at its other end to the detent, the object of the spring being to cause the detent to exert a dragging action upon the clutch-lever and thereby insure the proper operation thereof to effect disengagement of the fast and loose clutch members. Manifestly the spring is subjected to sudden and violent strains when the detent and clutch-lever are brought into mutual engagement, and in actual practice the springs often break, putting the apparatus out of use until a new spring is substituted, the spring having no support or guide when stretched and then released, this, in connection with the sudden and violent strains when stretched, appearing to be the reason for the undue breakage.

My present invention relates to clutch mechanism of the character described and it has for its object the production of novel and efficient means for improving the action of the detent whereby breakage of the controlling spring therefor is reduced to such a minimum that it is practically obviated.

The various novel features of my invention will be fully described in the subjoined specification and particularly pointed out in the following claims.

Figure 1 is a front view of a clutch mechanism with one embodiment of my present invention applied thereto, the detent being

shown in coöperation with the clutch-lever; Fig. 2 is a detached view of the detent-carrying arm and the parts mounted thereon, some of the parts being shown in section, and the cover plate on the arm is partly broken out; Fig. 3 is a cross-section on the line 3—3, Fig. 1, looking toward the right, showing the detent controlling spring and adjacent parts; Fig. 4 is a perspective view of the detent, detached.

Referring to Fig. 1, the main shaft *a*; the continuously-running belt-pulley *a*² thereon, the hub *a*³ fast on said shaft and on which hub the clutch-lever *b*⁴ is pivoted at *b*⁵; the spring *e* connected at one end with the clutch-lever, and at its other end to a stud *e*' on the hub; the rock-shaft *a'* having the attached arms *d'* and *b*², the rod *n*²¹ coöperating with arm *d'* to permit the rock-shaft to be turned by spring *f* to swing the arm *b*² toward the shaft *a* when the clutch is to be rendered inoperative, and the pawl *g* arranged to at times coöperate with the notch *g*⁴ and prevent recoil or backward rotation of the shaft, are and may be all as in said Patent No. 718569. The fast and loose members *a*⁶, *a*² of the clutch are disengaged when rotation of the clutch-lever *b*⁴ is arrested, as in said patent, and the parts so far described are in themselves not of my invention.

In accordance with my invention as herein embodied the upturned end of the arm *b*² is provided with a substantially L-shaped guideway or recess 1, 2, in which is seated the detent, shown separately in Fig. 4 and comprising an elongated shank 3 and a lateral head 4, the shank being movable longitudinally in the part 2 of the guideway, Fig. 2, ample clearance for movement of the head 4 being provided in the part 1 of said guideway. As shown the head of the detent projects laterally beyond the inner side of the arm *b*², while the lower end of the shank 3 extends below the lower end of the guideway and has rigidly attached to it a heavy abutment 5 having a socket 6 formed in its upper face, and preferably conical, as shown. A cover-plate 7 attached to the face of the arm *b*² covers the guideway and retains the detent therein, the lower end of said plate being notched at 8 to loosely embrace the abutment. At the upper end of the cover-plate, as herein shown, a second rigid abutment 9 is secured, opposite the abutment 5, and having an aperture 10 therein, Fig. 2,

which is substantially in alinement with the socket 6.

A combined spring-guide and support, shown as a stout spindle or rod 11 is slidably mounted at its upper end in the abutment 9, and its lower end is tapered or coned at 12 to seat loosely in the socket 6. Preferably the lower end of the spindle has an annular enlargement 13 thereon, and a strong controlling spring 14 is coiled around the spindle, said spring being only partly shown in Fig. 3, the spring being interposed between the abutment 9 and the enlargement 13, as shown clearly in Figs. 1 and 2. The spring 14 is somewhat compressed under normal conditions and by its expansive tendency acts through the abutment 5 to retain the detent in the position shown in Fig. 2, with the lower edge of its head resting against the lower edge of the part 1 of the guideway in the arm b^2 .

As will be manifest the abutment 9, which is fixed relatively to the arm b^2 and to the detent, supports the spring 14 at its upper end when compressed by upward movement of the abutment 5 movable with the detent, the spindle at such time sliding longitudinally in the abutment 9, the connection of the spindle with the abutment 5 permitting any slight rocking movement to prevent bending, and it will be seen that the spindle supports the spring throughout its length and prevents any lateral displacement or distortion thereof. This causes the spring to be held true and in correct position for best resisting compression strains, so that the latter act directly longitudinally of the spring, and breakage or cracking cannot be caused by lateral distortion or bending. As a result the spring not only operates with greater efficiency but its life is greatly increased and any tendency to break is reduced to a minimum.

The operation of the device is self-evident, movement of the arm b^2 toward the shaft a bringing the detent head 4 into the path of and arresting rotation of the clutch-lever b^4 , to thereby render the clutch inoperative. When the clutch-lever hits the detent it moves it upward, Figs. 1 and 2, moving the abutment 5 toward the relatively fixed abutment 9, and the spring 14 is compressed, cushioning the blow and providing the drag-

ing action which insures the proper engagement between the detent and the clutch-lever 55 to disengage the clutch members.

While my invention is shown for convenience of illustration in connection with the clutch device of a sewing machine, it is not restricted thereto, but can be used with other 60 apparatus wherein a similar action is required.

Having fully described my invention, what I claim as new and desire to secure by Letters Patent is:—

1. In a device of the class described, a rotary clutch-lever, a movable arm having a guideway, a detent having a shank longitudinally movable in the guideway and extended beyond the lower end thereof, and 70 provided on the extended part with a rigid, socketed abutment, an apertured, oppositely located and relatively fixed abutment on the movable arm, a guide-spindle loosely seated at one end in the socket of the abutment carried by the detent shank and 75 slideable in the opposite, relatively fixed abutment, and a controlling spring for the detent, coiled about the spindle and interposed between said abutments, operative movement 80 of the arm effecting coöperation of the clutch-lever and detent and moving the latter against the stress of the spring.

2. In a device of the class described, a rotary clutch-lever, a movable arm having an 85 abutment fixed thereon, a detent having a shank carried by and movable longitudinally on the arm and provided with a socketed abutment, a spindle tapered at one end and seated in the socket and in sliding engagement with the other abutment, an annular enlargement on the spindle adjacent its end resting in the socketed abutment, and a 90 spring coiled about the spindle and resting at one end against said enlargement and at 95 its other end against the relatively fixed abutment, the spindle guiding the spring when compressed and preventing lateral displacement thereof.

In testimony whereof, I have signed my 100 name to this specification, in the presence of two subscribing witnesses.

JOHN MAITLAND. [L. s.]
